THE NATIONAL LITHOGRAPHING COMPANY,
WASHINGTON, D. C.

UNITED STATES PATENT OFFICE.

THOMAS A. LEE, OF KANSAS CITY, MISSOURI.

TENSION-ROD.

SPECIFICATION forming part of Letters Patent No. 513,794, dated January 30, 1894.

Application filed April 30, 1892. Serial No. 431,369. (No model.)

To all whom it may concern:

Be it known that I, THOMAS A. LEE, of Kansas City, in the State of Missouri, have invented certain new and useful Improvements 5 in Tension-Rods for Fireproof Floors, Roofs, Ceilings, Walls, Cement Area-Walks, and the Like, of which the following is a description, reference being had to the accompanying drawings, which form a part of this specification.

The object of my invention is to produce a tension rod having a very large cement engaging surface, whereby it may contribute greater strength to the blocks of terra cotta, 15 lumber, or other building material, and to the mass of concrete, used in the construction of fire proof floors, roofs, ceilings, walls, cement area walks, and the like, and to these ends and purposes it consists of a tension rod, 20 constructed, arranged, combined, and used, substantially in the manner hereinafter described, illustrated, and claimed.

In the accompanying drawings, Figure 1 is 25 an isometric projection showing one form of my tension rod or cable embedded in a mass of plaster, concrete, or other building material. Fig. 2 is a similar view showing my tension rod as used in one construction of flooring. Figs. 3, 4, 5, 6, and 7, are detailed views 30 of several types of my tension rod or cable.

In the drawings like letters of reference indicate like parts.

In the construction of my rods or cables I 35 preferably employ steel wire of high tensile strength which has been drawn through a die, thus obtaining greater uniformity and reliability with a much higher tensile strength and elastic limit than the usual rolled bars or rods possess. The wire is cut into convenient 40 lengths for twisting—say fifty or seventy feet—and washers or separating devices hereinafter more fully described, are strung upon the wires or placed between several wires laid side by side, at desired intervals. The number 45 of wires, preferably three or four, are then made fast to end clamps provided with tension attachments and means for twisting the wires and the cable. The wires are then twisted and the washers or spreaders thereby 50 bound firmly in position.

My washers or spreaders consist of metal blocks, plates, rings, or flat strips. These

hold the wires apart at the points where they occur, and thereby greatly increase the cement engaging surface of the cable or rod. 55 They also serve to hold the wires while being twisted and in certain types project above the rod and form anchor plates for more securely retaining the rods in their surrounding masses of cement.

In Fig. 4 I have shown in sections and in side view a piece of tension rod provided with the washers of my most preferred form. These consist of plates A provided with perforations through which the several wires of 65 the tension rod are strung.

Figs. 3 and 5 show my cables provided with devices for merely spreading the wires apart and presenting cement engaging surfaces.

Fig. 6 shows my rod provided with plate 70 strips forming spiral ribs around the rod. I prefer to cut these plate strips of lengths equal to the wires to be twisted and of iron similar to thin hoop iron and possessing high tensile strength. When placed between the 75 wires as shown in the figure and twisted with them, these strips form a spiral rib between each pair of adjacent wires, giving great cement engaging surface and resistance to end stresses or thrusts. When the plate strips 80 are made of metal possessing different coefficients of expansion with heat, I preferably cut the strips into short lengths. In the use of these plate strips I am able to form tension rods of metals having different coefficients, without injury to the floor structure. 85

In Fig. 7 I show a modification of Fig. 4, in which circular wires are replaced by triangular wires, the washers being adapted to such change. The triangular wires may be rolled 90 or drawn in the process of manufacturing, or prepared by other methods; and I make use of them merely for the advantage gained by the angular spaces formed between them.

When spreaders are used as in Figs. 3 and 95 5, I bind the wires together upon the spreaders, during the process of twisting, by wrapping them with a small cord or wire.

In Fig. 1 of the drawings is shown the manner of using my tension rods to increase the 100 transverse strength of building blocks or beams. The tension rod is embedded in the cement or concrete near that face of the beam or block which will be put in tension by the

load. By so doing I avoid the usual iron beam and flat arch construction; for the tile work of burnt clay or other material possesses the requisite strength for compression and 5 my tension rods relieve it of the tensile strains which, without them, it would not be capable of withstanding.

In Fig. 2 is shown a construction of flooring in which two layers of blocks are used 10 with cement filling between them. My tension rods are shown embedded between adjacent blocks of the lower layer in masses of cement D. I find it preferable, especially with narrow wall bearings, to place a washer 15 upon the projecting end of the tension rod, and to turn over or head up on the washer the ends of the wires, as shown at c in Fig. 2. This washer gives a bearing surface upon the 20 ends of the tiles and thereby relieves the cement about the end of the rod from excessive shearing strains.

Besides giving greater and more tortuous exterior surface to tension rods, my invention, by furnishing abrupt shoulders to engage 25 the cement, effectually anchors the cable or rod in the cement. I am therefore enabled to use a cement of weaker composition, and I find that lime mortar tempered with cement in the usual way possesses ample strength 30 for forming the union between by tension rods and the hollow tiles, blocks of cement, or concrete, which may be used in the construction of fire proof floors, roofs, walls, area walks and the like. I do not find it any advantage, therefore, to substitute strands in my 35 cable consisting of several small wires each, for the rougher surface thereby gained is of less advantage than is the stiffness obtained by strands of single wires of greater size. 40 The latter will remain straight when laid in position without being stretched.

When my rods have been completed by the process of twisting, they are cut into proper lengths, and, when desired, a washer 45 of large bearing surface is provided for each end of each rod to extend over the faces of the tiles and bear any excessive stress that may come upon the rod near the ends.

I have now set forth several embodiments 50 of my invention as constructed for various uses. In a patent issued to me October 13, 1891, and numbered 461,028, I have shown the way in which artificial joists may be constructed from terra cotta tiles and tension rods, and in this present patent I have set

forth a further development of the construction therein shown or described.

I do not claim broadly a tension rod of twisted construction, for I am aware that such a device has heretofore been used. Neither 60 do I in this patent claim a spiral or twisted rod consisting merely of two or more strands or wires twisted or laid together, as these form the subject matter of a patent No. 505,664, granted to me September 26, 1893, 65 and entitled non-shearing rods for strengthening concrete work. In that patent also, I include a specific claim for the spiral ribs shown in Fig. 6, since such claim could not be made in the present patent. 70

What I do claim, and desire to secure by these Letters Patent, is the following:

1. A rod for the purposes described consisting of two or more strands twisted together but held apart at intervals by separating 75 pieces for increasing the cement engaging and shearing surface of the said rod substantially as set forth.

2. A rod for use in concrete, mortar, cement, and the like, consisting of two or more strands 80 of wire or small rods, and a separating piece or pieces placed between the strands of the said rod, the strands of the rod being held together between the said separating pieces, but allowed to separate around the said pieces, 85 whereby greater cement engaging surface is produced, substantially as, and for the purposes, set forth.

3. A tension rod for the purposes described consisting of two or more strands or wires, 90 twisted together, and of separating pieces held in position by the said strands or wires and projecting from the said rod, whereby concrete or other embedding material may more firmly cling to the said rod substantially as set forth. 95

4. A twisted tension rod for the purposes described provided with pieces of metal or other material strung thereon, substantially as set forth. 100

5. A tension rod for the purposes described consisting of two or more strands, of angular cross section, secured together, substantially as set forth.

In testimony whereof I have hereunto set 105 my hand this 11th day of April, 1892.

THOMAS A. LEE.
